United States Patent Office.

STEPHEN PUFFER, OF OXFORD, NEW YORK.

Letters Patent No. 65,602, dated June 11, 1867.

IMPROVED CAR-COUPLING.

The Schedule referred to in these Letters Patent and making part of the same.

TO ALL WHOM IT MAY CONCERN:

Be it known that I, STEPHEN PUFFER, of Oxford, in the county of Chenango, and State of New York; have invented a new and improved Car-Coupling; and I do hereby declare the following to be a full and exact description thereof, reference being had to the accompanying drawings, forming a part of this specification, in which—

Figure 1 is a plan view thereof showing its operation in coupling railroad cars.

Figure 2, a central vertical section thereof, showing the coupling-link reversed, the automatic movements of the coupling-link by the contact of the bumpers being indicated by red and blue dotted lines, and the release of the link to prevent its automatic coupling by red positive lines.

Figure 3 is a side elevation of the coupling, illustrating the coupling-link as thrown over into an engaging position by the contact of the bumpers or otherwise; and

Figures 4 and 5 are detached views of a bumper and of the reversible bumper-block fitting alike in either bumper to permit of the adjustment of the coupling-link on either side at pleasure.

Similar letters indicate like parts in each of the figures.

The nature of my invention consists of an improvement in the arrangement of pivoted swinging-links or loops for coupling automatically railroad cars by extending the ends of the link beyond their pivot apertures and imparting thereto a cam shape, to be acted upon automatically by the contact of the bumpers; and also in the combination of a mortised bumper-block with the bumper of a coupling opposite that to which the link is pivoted, for the purpose of acting upon cams on said link to throw it over and cause its engagement when the bumpers come together.

The bumpers A B in my improved car-coupling may be made solid if preferred. A square recess, *a*, (see fig. 4,) whose lower side is about on a line with the centre of the bumper, is cut into and across the end or face of each to receive the axis *x* of the coupling-link, and the lower edge of said face is also cut back in a line parallel to said recess, so as to leave a tongue, *b*, projecting between the two, coinciding with the bumper in width. In the recess *a* of one bumper, (as B, fig. 1, or A, fig. 2,) I place a bar or axle, *x*, and secure it therein at pleasure by means of a pivot-pin, *D*, in an aperture pierced so as to pass centrally through the upper piece above the recess and through the tongue *b*, as well as through a pivot-hole pierced in said axle in the centre of its length. The inner edge or face of said axle *x* is so curved as that the axle may turn freely in its pin in a horizontal plane. To the ends of the axle are pivoted or hinged the ends or arms of a suitably curved coupling-link or bail, *E*, which is thus of sufficient length to swing down entirely below the bumper and back under the same, (see red dotted lines, fig. 2.) Upon the face of the opposite bumper (A, fig. 1, or B, fig. 2) I place a bumper-block, *F*, consisting of a suitable block somewhat longer than the width of the bumpers, having a mortise cut longitudinally and centrally through it of sufficient size to receive and embrace closely the tongue *b* formed in the face of each bumper, and so formed as to fit accurately and snugly against or upon said face. The ends of this block, projecting outwardly on either side of the bumper when it is fitted thereon, have their front faces bevelled upwardly on the upper edge, as illustrated at *c*, in figs. 3 and 5, from a point about midway of the width of said block. This block *F* is secured in place upon the end of either bumper by the same pin *D*, which otherwise serves to secure the coupling-link, this pin passing through apertures pierced in the block above and below its mortise, so as to be in register with those in the bumper when properly placed thereon. The ends of the link or bail *E* are provided with enlarged cam-plates or ears, *e e*, and the ends of the axis upon which said coupling-link is pivoted pass these ears in the upper portion thereof at points in front of the juncture of the coupling-link with said ears, as seen in fig. 3, in such manner as that when the coupling-link is elevated in a vertical position the front edges of said ears shall not project beyond the face of the bumper; but if it be thrown back, as seen in dotted lines, fig. 2, the lower ends of said ears shall project beyond and in front of the face of the bumper. The front edges of these ears are so curved as to form cams having the pivot of the coupling-bail or link *E* for a centre of motion. One or all of the coupling-links *E* in a train may be attached to a cord, *s*, (as shown in fig. 3,) leading within reach of the conductor or engineer, so that either may thereby uncouple the cars at pleasure.

The operation of my improved coupling is as follows: The axle *x* of the swinging-link *E* is inserted in the

recess *a* of the bumper and there pivoted and secured by a bolt or pin, *D*. The mortised block *F* is fitted upon the opposite bumper and there secured by a corresponding pin. If now the link *E* be swung forward and allowed to drop over its bumper, as shown by red positive lines in fig. 2, and the cars are pushed together so that the bumpers *A* and *B* strike, the link will swing back freely under its bumper and without coupling; but if, on the other hand, the link be first thrown back so as to lie over upon its bumper, as indicated in red lines, fig. 1, and the bumpers be now brought together by the movement of the cars, then the cams or ears of the link, projecting beyond the face of its bumper, (see dotted lines, fig. 3,) will be struck below their pivot centres by the lower portion of the projecting ends of the block *F* on the opposite bumper, and thus thrown back, so as to throw the coupling-link over and cause it to fall forward over the head of the pin *D* on said opposite bumper, in a position to engage therewith when the bumpers are drawn apart, as shown in fig. 1, and in partial section fig. 2. As the link *E* has free play both horizontally and vertically, and swings also freely upon the pin *D*, whose head is grooved to receive and engage it, it cannot be lifted therefrom nor the bumpers be uncoupled by any of the usual movements of the car, but if either car turn over the link is thereby instantly uncoupled. By means of the cord *s* the engineer and conductor may lift the coupling-links at pleasure.

I do not claim a coupling-link swinging both horizontally and vertically and encircling the bumper, nor do I claim a swinging-link having arms extending beyond its pivot; but I claim as an improvement, and desire to secure by Letters Patent—

1. The combination of cams *e* with the pivot ends of a detachable, swivel-jointed coupling-link *E*, when said ends are so arranged as to be struck by the collision of the cars when thrown back upon the bumper.
2. I also claim the combination of a detachable bumper-block with either bumper of a railway car and with a swinging coupling-link, all substantially in the manner and for the purpose set forth.

The foregoing specification of my improved car-coupling signed by me this 30th day of March, A. D. 1867.

STEPHEN PUFFER.
